UNITED STATES PATENT OFFICE.

HOMER T. YARYAN, OF TOLEDO, OHIO.

APPARATUS FOR EXTRACTING TURPENTINE AND ROSIN FROM RESINOUS WOODS.

964,728.

Specification of Letters Patent. Patented July 19, 1910.

Application filed October 21, 1909. Serial No. 523,781.

To all whom it may concern:

Be it known that I, HOMER T. YARYAN, a citizen of the United States, residing at Toledo, in the county of Lucas and State of Ohio, have invented certain new and useful Improvements in Apparatus for Extracting Turpentine and Rosin from Resinous Woods; and I do declare the following to be a full, clear, and exact description of the invention, such as will enable others skilled in the art to which it appertains to make and use the same, reference being had to the accompanying drawings, and to the figures of reference marked thereon, which form a part 15 of this specification.

In the process of extracting turpentine from resinous woods by distillation in a current of steam and the subsequent treatment, in the same vessel, of the wood with a 20 solvent,—such, for instance, as naphtha,—to extract the rosin, there is constant danger during the steaming operation of contaminating the turpentine distillate with the solvent, due to leaking valves or to the carelessness of workmen in not tightly closing the valves. This danger is greatly increased 25 when a number of extractors are in operation simultaneously, all of the extractors being connected with a common supply of solvent, some of the extractors being under 30 treatment for the recovery of the turpentine while others are being treated with the solvent for the recovery of the rosin. As it is almost impossible to separate the solvent 35 from the turpentine when the contamination has once taken place, the importance of some means for rendering impossible the accident referred to is apparent.

My invention relates to and its object is 40 to provide means for overcoming the objections and difficulties above indicated, and, more particularly, to provide means for preventing the flow of a solvent in which extractor during the process of distillation of 45 resinous woods for the recovery of turpentine.

I attain these objects by means of the devices, and arrangement of parts hereinafter described, and shown and illustrated in the 50 single figure of the accompanying drawing which illustrates, in side-elevation, a simple form of my apparatus.

In the drawings, 1 is an extractor designed to receive the comminuted wood to 55 be treated, and provided with suitable doors for charging and discharging the extractor

and provided with any required means for supplying the extractor with steam and for heating the contents of the vessel, as by steam supply pipe 1^a, and, if required, means 60 for placing the interior of the extractor under a vacuum through discharge pipe 1^b. As these features of the device form no part of the present invention, it will be unnecessary to here further describe the same, it being understood that the extractor is adapted and arranged for the distillation of wood for the recovery of turpentine and for the subsequent treatment of the wood with a solvent to extract the rosin.

2 is a reservoir for the solvent and 3 is a pipe leading from such reservoir to the extractor. In the pipe 3 are two hand-valves 4—4.

5 is a pipe connected with the pipe 3 between the two hand-valves 4—4 and leading to a vacuum pump 6, supplied with steam through steam pipe 6^a. The pipe 5 is suitably valved, as at 7, to permit the closing, at will, of the passage between the pipe 3 and the pump.

During the operation of distillation for turpentine, the valves 4—4 are closed, the valve 7 is opened, and by means of the pump, a partial vacuum is maintained in the pipe 5. Now, if through negligence, accident or defective valves, there is any leak which would permit the flow of solvent from the reservoir 2 to the extractor, the solvent will be drawn to the pump instead of entering the extractor. If the contents of the extractor are being treated under a partial vacuum, the vacuum created by the pump 6 should be superior to the vacuum in the extractor. The same result above described may be obtained by using the pump 6 as a force-pump for air or gas or any suitable fluid instead of as a vacuum-pump, as it will be understood that pressure of any suitable medium,—superior to the pressure in the pipe 3,—being applied through the pipe 5 between the valves 4—4, the flow of solvent into the extractor would be prevented. In practice, however, I prefer to connect the pipes 3 and 5 with means for producing a vacuum.

Having described my invention, what I claim and desire to secure by Letters Patent is,—

1. In a device of the character described, an extractor for the treatment of resinous woods with a solvent, a solvent supply pipe leading to said extractor, two valves in said

23 964,728
pipe and means for producing in said pipe—
between said two valves—a pressure different
from the pressure within the extractor.

2. In a device of the character described,
5 an extractor, a container for a solvent, a
pipe leading from the container to the ex-
tractor, two valves in said pipe, a pump and
connections between said pipe—intermediate
said two valves—and said pump.
- 10 3. In a device of the character described,
an extractor, a container for a solvent, a

pipe leading from the container to the ex-
tractor, two valves in said pipe, said pipe
having an outlet between said two valves,
and means for, at will; opening or closing 15
said aperture.

In testimony whereof I affix my signature
in presence of two witnesses.

HOMER T. YARYAN.
